UNITED STATES PATENT OFFICE.

AARON COLEMAN, OF NEW YORK, N. Y.

DESIGN FOR A SUSPENDER-END.

SPECIFICATION forming part of Design No. 31,773, dated October 31, 1899.

Application filed October 7, 1899. Serial No. 732,968. Term of patent 7 years.

To all whom it may concern:

Be it known that I, AARON COLEMAN, a citizen of the United States, residing in the borough of Manhattan, city, county, and State of New York, have invented and produced a new and original Design for a Suspender-End, of which the following is a specification.

In the accompanying drawing I have illustrated a suspender-end embodying my design.

10 A represents a suspender-end.

The leading or essential features of my design consist of the endless cord a , so arranged as to form loop ends a' , which are adapted to be connected with the shoulder-straps of a 15 pair of suspenders, and the web portion a^2 , which is connected to the cord a intermediate the loop ends a' . A buttonhole-strap a^3 is

connected with the web portion a^2 , and a buckle a^4 is carried by the web a^3 .

It is evident that the design is applicable 20 equally to the back or front of suspenders or to articles of like nature.

Having described my invention, what I claim as new, and desire to secure by Letters Patent, is—

25 The design for a suspender-end, substantially as shown and described.

In testimony whereof I have signed my name to this specification in the presence of two subscribing witnesses.

AARON COLEMAN.
